UNITED STATES PATENT OFFICE.

LUCIUS P. HOYT, OF AURORA, ILLINOIS.

ENDLESS-CHAIN BED FOR WOOD-WORKING MACHINES.

SPECIFICATION forming part of Letters Patent No. 275,213, dated April 3, 1883.

Application filed January 24, 1883. (No model.)

To all whom it may concern:

Be it known that I, L. P. HOYT, of Aurora, Illinois, have invented certain Improvements in Surfacer Chain-Beds, which invention relates more especially to the construction of the lags or slats which, jointed by the links, form the traveling bed of a wood-working machine.

It further relates to the surface construction of the stationary bed which forms the support for said lags.

In the drawings forming part of this specification, Figure 1 shows the chain-bed and stationary bed arranged under the surfacing-cylinder of a wood-planer. Fig. 2 is a plan view of the under side of one of the slats or lags. Fig. 3 is a cross-section to line $x-x$ of Fig. 2, somewhat enlarged. Fig. 4 shows a plan or face view of the stationary bed.

Like letters of reference indicate like parts.

The object of my invention is to provide a good bearing-surface of the lags A upon the stationary bed B to reduce friction and to prevent uneven wear of the lags A and stationary bed. For this purpose I provide the cast-iron or cast-steel lag A, at its bearing-surfaces, $a a$, with one or more slightly-tapering notches or recesses, $d d$, which may be formed in the casting, or may be otherwise inserted, if so preferred. These recesses are then filled with anti-friction metal $c c$, preferably an alloy of not too brittle a nature. After pounding this anti-friction metal tightly into the cast-iron recesses the surfaces are planed as usual to secure even thickness of the lags.

The stationary bed B is provided with a steel rail or plate, b , to prevent uneven wear, and to provide more particularly against wearing hollow under the cutting-cylinder. The face of this stationary bed, Fig. 4, may also be provided with a number of recesses, d' , similar to those in the bearing-surfaces of the lags. Holes

may be drilled into the steel rail b , and all of these holes and recesses are filled with anti-friction metal c , as shown above.

The cast-iron lag is greatly injured by particles of sand or dirt carried along by the stuff to be planed while traveling along the stationary bed. It will soon become rough, attrite, uneven, inaccurate. All of these qualities will exaggerate by longer use until the lag is entirely unfit for further use, worthless.

The anti-friction metal fillings $c c$ on my improved lag, while procuring a better friction-surface by themselves without affecting the strength of the lag, will embed such particles of dirt and prevent their harming the cast-iron surface portion of the lag. After a short time the anti-friction metal will fill up the pores of the respective surfaces, and together with the lubricating material will form an unctuous film, covering the bearing-surfaces of the traveling lags, as also the stationary bed B.

I do not deem it necessary that both the traveling lag A and the stationary bed B should be provided with anti-friction metal fillings c , though this might be done, if so preferred.

Having thus described my invention, what I claim, and desire to secure by Letters Patent, is—

1. The lag A of a traveling bed, provided at its bearing-surfaces $a a$ with one or more recesses, $d d$, which are filled with anti-friction metal $c c$, for the purpose as described and set forth in the specification.

2. The stationary bed B, provided at its upper bearing-surface with holes or recesses filled with anti-friction metal, for the purpose as specified.

LUCIUS P. HOYT.
